UNITED STATES PATENT OFFICE.

LAWRENCE B. STEVENS, OF RUTHERFORD, NEW JERSEY.

SWITCH.

No. 897,559.

Specification of Letters Patent.

Patented Sept. 1, 1908.

Application filed June 1, 1906. Serial No. 319,682.

To all whom it may concern.

Be it known that I, LAWRENCE B. STEVENS, a citizen of the United States, residing at Rutherford, in the county of Bergen and State of New Jersey, have invented a new and useful Improvement in Switches, of which the following is a description.

My invention relates to switches, designed for use in connection with any one of a series 10 of batteries or other sources of electrical energy, whereby said series of batteries, etc., may be successively cut into and out of the electrical circuit, or whereby said batteries may be connected up in parallel.

15 My invention is capable of a wide range of use where the arrangement of batteries or sources of electrical energy are, as above stated, but is more particularly designed for use in connection with the ignition mechanism of hydro-carbon propelled motors or vehicles.

20 By the arrangement of the structure hereinafter to be described, it becomes practically impossible to operate the switch without the use of a key of peculiar shape, the structure being so arranged that the insertion of the key into the mechanism throws into operative position a cut-out, thereby making it possible to operate the switch for 25 cutting-in the various batteries, while the withdrawal of the key from the mechanism, throws the cut-out into inoperative position, and locks the structure in such a way as to prevent unauthorized operation.

30 In the accompanying drawings, forming a part of this specification, Figure 1 illustrates a rear view of the switch mechanism showing the cut-out in locked engagement with the switch. Fig. 2 illustrates a like view of the 35 mechanism with the cut-out in operative position, with the switch thrown to the first contact, and Fig. 3 illustrates a central cross-section on line x of Fig. 2.

Similar letters of reference refer to like 40 parts throughout the specification.

The case A is of cup-shape as shown in Fig. 3, having a central aperture a forming a bearing for the shaft b, upon the outer end of which is rigidly secured the operating button 45 B. Rigidly secured to the inner end of the shaft b, is the drum c. Mounted also upon the shaft b to rotate therewith, is the contact spring d. The conductor e is located between the contact spring d and the bottom 50 of the case A, so as to be in metallic contact with the contact spring d. This conductor e

leads laterally from the pin f with which it is in metallic contact. Pivoted upon the pin f is the cut-out g, of peculiar shape and contour, having one arm g' provided with a pawl-point for engagement with the notch or stop c' in the drum c. The opposite end of the cut-out g is bifurcated as at g'' for a purpose hereinafter to be described. The conductor h is secured in the bottom of the case 60 A by means of the screw pins h', as shown. The forward end of the conductor h is bifurcated as shown in Fig. 3, for the purpose of receiving the arm g' of the cut-out g, when in the position illustrated in Fig. 2. The other 65 end of the conductor h is provided with means for connection with a circuit wire, such means consisting of the nuts h'; a binding post or headed screw would serve the purpose equally well. Secured within the 70 case A is also the conductor i, having the contact projections i' and i'' as shown. The end of the conductor i is also provided with the means i' for connection with the circuit wire. The contact projections i' and i'' lie 75 within the path of the contact spring d. There is also secured within the case, the conductor k, having the contact projections k' and k'', each lying in the path of the contact spring d. The terminal k' similar in every 80 respect to the terminals h' and i'. The key hole l opens laterally into the case A, adjacent to the bifurcated end g'' of the cut-out g, such key hole being continued into the bottom of the case, as a guide channel l' 85 for the key. The key m is clearly illustrated in Fig. 3, as being constructed of a strip of metal having a longitudinal slot m', and a terminal open slot m'', said slots being separated by the cross-portion n.

90 The key hole l opens laterally into the case A, adjacent to the bifurcated end g'' of the cut-out g, such key hole being continued into the bottom of the case, as a guide channel l' 90 for the key. The key m is clearly illustrated in Fig. 3, as being constructed of a strip of metal having a longitudinal slot m', and a terminal open slot m'', said slots being separated by the cross-portion n.

95 In practice it is customary to connect the like poles of the batteries o, o', or other sources of electrical energy directly to the terminal h', the other poles of the batteries 100 being connected respectively to the terminals i' and k', leading through the necessary electrical instrument as for example, the induction-coils p, p' respectively as illustrated in Fig. 2.

105 With the instrument having its parts in the position illustrated in Fig. 1, that is, with the key withdrawn, it will be noted that the pawl-point g' falls in the notch c' of the drum c, which position is assumed only when the contact spring d is in the position shown, 110 against the stop g. Upon the insertion of the key m into the key-hole l and pushing the same

home, it will be noted that the cross-piece *n* will strike the inner-most fork *g*² of the bifurcated part of the cut-out *g* and throw it into the position illustrated in Fig. 2, said fork 5 resting against said cross-piece *n*, thereby locking the arm *g*' into contact with the forked end of the conductor terminal *h*. In this position, the drum *c* is released and the contact spring *d* may be turned through the 10 medium of the button *B*, into contact with any one of the contact projections *i'*, *k'* or *i², k²*.

It will be noted that when the contact spring *d* is in electrical connection with the 15 contact projection *i'*, the circuit through battery *o'* is closed, while when the contact spring *d* is swung into contact with the contact projection *k'*, the battery *o'* is cut-out and the battery *o* is cut-in. Further rotation 20 of the contact spring *d* into contact with the projections *i²* and *k²* will cut-in both batteries *o* and *o'* in parallel. It will be further noted that with the contact spring *d* in any other position than that shown in Fig. 1, it 25 will be impossible to fully withdraw the key from the key hole *l*, since the pawl-point *g*' will be brought against the convex surface of the drum *c*, thereby preventing further rotation of the same, and leaving the other fork 30 of the cut-out *g* behind the cross-piece *n* of the key. Upon the rotation of the drum *c* into the position illustrated in Fig. 1, the notch *c'* will come into the position for the pawl-point *g*' to fall therein, and thereby permit the complete withdrawal of the key. 35

From the above description, it will be noted that with the key withdrawn, it will be impossible to manipulate the switch for the reason that it is locked into the position illustrated in Fig. 1, and that it will be impossible to completely withdraw the key until the switch is thrown to the position illustrated in Fig. 1.

A switch of the character described is particularly adapted for use upon gasoline propelled motor vehicles, wherein the explosion of the gas in the motors of the vehicles is made by the use of what is known as a "sparking coil".

By the use of my invention, it is not only possible to cut-in either of the batteries, individually and successively, but also possible to cut them both in in parallel. Other series of batteries can be used in connection 55 with a switch of this type, by providing sepa-

rate contact points for each battery, substantially as illustrated in the drawings, the limit to the number being determined only by the size of the switch.

I claim:

1. An electric switch, comprising a rotatable contact spring provided with a locking member, an electrical connection leading from said spring to a source of electrical supply, a cut-out in said connection, said cut-out being provided with a locking member, means for operating said cut-out to break said connection and lock said spring against rotation. 60

2. An electric switch, comprising a rotatable contact spring, an electrical connection leading from said spring and provided with means for connection with an electric circuit, a locking member secured to said contact spring, a locking cut-out in said electrical connection and a key for operating said cut-out to break said connection and lock said contact spring against rotation. 70

3. In an electric switch, the combination with a plurality of conductors leading from a plurality of sources of electrical supply, a contact spring designed for electrical connection with each of said conductors in succession, a common return conductor leading to said sources of electric supply, said return conductor being provided with a cut-out, having a locking member, and means for operating said cut-out to interrupt the circuit through said return conductor and lock said contact spring out of contact with said plurality of conductors. 80

4. In an electrical switch, the combination with a plurality of electrical supply conductors and a common return conductor, of a rotating contact spring for connecting each 95 of said supply conductors with said return conductor, a locking member rigidly secured to said contact spring, and a pivoted cut-out in said return conductor, said cut-out having a locking member, and means for actuating 100 said cut-out to interrupt the circuit through said return conductor and lock said contact spring against rotation.

This specification signed and witnessed this 24th day of May 1906.

LAWRENCE B. STEVENS.
